YARN TWISTING OR WRAPPING DEVICE

Edwin G. Egge, Providence, R. I., assignor to
United States Rubber Company, New York,
N. Y., a corporation of New Jersey

Application April 25, 1951, Serial No. 222,780

7 Claims. (Cl. 57—18)

1

This invention relates to a small yarn guiding cap that is rotatably mounted upon the upper end of a yarn supporting spindle and is adapted for use, when such spindle is rotated, as a yarn twisting or yarn wrapping device.

The cap of the present invention is an improvement over the cap shown, described and claimed in my Patent No. 2,488,970 for Core Covering Device. In working with the cap of said patent it was found desirable to provide means for controlling the tension of the covering yarn as it passes from the supply package to the core covering position.

One important feature of the present invention resides in a core covering or yarn twisting cap that can be operated at very high speed and which comprises a cylinder or ring having a bridge bar spanning such cylinder or ring and arranged so that the yarn supplied to this cap from a rotating package can be given any desired tension by looping it partly or entirely around the bridge bar as it approaches the central guide hole of the cap.

The cap of the present invention preferably is no larger in diameter than the package supporting spindle, so that the package with its adapter can be doffed without removing the cap from its spindle. Furthermore the cap is so small and light and it controls the yarn so well that it is possible to rotate its supporting spindle at very high speed, such as 20,000 R. P. M. or higher.

The cap is rotatably supported at the upper end of the yarn carrying spindle by an anti-friction bearing such as a ball bearing, and when the spindle is rotating at high speed the cap will usually turn only a few hundred R. P. M. relatively thereto, to accommodate the unwinding of the yarn from its package.

The cap of the present invention may be used to twist a single yarn, or to ply two or more yarns together at high speed, and to control accurately the tension of the yarns during such twisting or plying operation. It however was developed primarily for use as a core covering device where it is used to guide and tension the covering yarn as it is supplied to the core covering position to cover a rubber thread.

This cap preferably has a cylindrical body, as above stated, which body fits snugly over its supporting bearing and is provided with a tension bar or bridge bar that forms the upper portion of the rotating cap. This bridge bar is connected to the cylindrical body by two vertical legs. A yarn guiding hole is preferably formed in each leg, and a central hole for receiving the core or

2

yarn is formed in the central portion of the bridge bar. A cap constructed in this manner is symmetrical in design and does not disturb the balance of the spindle on which it is mounted. It is free from lateral projections that might strike and injure the machine attendant, or produce objectional windage forces. It is easy to thread up in various ways to secure the desired yarn tension, and has other advantages as will hereinafter appear.

While the present invention resides primarily in the construction and operation of the above described spindle cap, the construction of the anti-friction bearing that supports the cap is also important and particularly the arrangement whereby when the cap is used upon a core covering spindle, the talc dust, released from the rubber core thread in the hollow spindle, is effectively prevented from reaching the anti-friction bearing and interfering with its rotation. This protection of the anti-friction bearing from talc is secured largely by providing an inside bearing race that is tightly attached to the rotating hollow spindle, and an outside bearing race that is secured directly to the cap. Such a construction prevents talc from entering the bearing from a point below the same. Talc is further prevented from reaching the bearing by providing above the bearing an outwardly flaring head that extends over the bearing, and by providing talc discharge holes below the bearing.

The above and other features of the present invention will be further understood from the following description when read in connection with the accompanying drawings; wherein

Fig. 1 is a side elevation showing the cap of the present invention applied to a core covering device;

Fig. 2 on a larger scale is a vertical sectional view through the upper portion of the rotating hollow spindle and cap of Fig. 1;

Fig. 3 is a side view of the cap of Fig. 2 shown removed from the means which supports it on the rotating spindle; this view shows how to thread up the covering yarn to secure a minimum amount of tension;

Fig. 4 is a vertical sectional view through the cap and shows the covering yarn wound around the bridge bar to secure a high amount of tension;

Fig. 5 is a vertical sectional view through the cap taken at right angles to Fig. 3;

Fig. 6 is a top plan view of the cap of Fig. 5;

Fig. 7 is a view similar to Fig. 1 but shows how

the present invention may be employed to twist a single yarn;

Fig. 8 is a vertical sectional view through the upper part of the spindle and cap of Fig. 7;

Fig. 9 shows the cap as used to form a ply yarn and as applying a moderate amount of tension on such yarn; and

Fig. 10 is a view similar to Fig. 9 but shows how to apply high tension upon the yarn.

The cap of the present invention may be used as shown on Sheet 1 of the drawings to produce a covered strand, such as a covered rubber thread, or it may be used as shown on Sheet 2 of the drawings to form a twisted yarn or ply yarn. It can be employed on various types of core covering machines or yarn twisting machines now in use.

Now referring to the construction shown on Sheet 1, the device is illustrated in Fig. 1 of the drawing as applied to a motor driven core covering spindle such as shown in the patent above cited, but may also be used upon belt driven core covering spindles.

In the drawings, 10 designates the upper end portion of an electric motor for driving the covering spindle 11. This spindle is made hollow and projects upwardly a substantial distance from the motor casing as shown to support and rotate a yarn package 12 at high speed. The yarn of this package is wound upon the usual paper tube 13, which tube fits snugly upon an adapter, comprising a tubular core secured to the head 13'. This adapter serves to center and support the tube 13 of the package upon the spindle 11.

The apparatus so far described by reference numerals is old and well known and constitutes one of a number of types of core covering units which may be provided with the core covering means contemplated by the present invention and which will now be described.

The hollow spindle 11 extends upwardly, as shown, some distance beyond the upper end of the yarn package 12, and the upper end of this spindle has mounted thereupon a freely rotating top piece or cap 14 adapted to guide and tension the covering yarn. This cap, as will be apparent from Figs. 2 to 6 inclusive, comprises a cylindrical sleeve 15 to which is secured in elevated relation thereto a bridge member comprising the bridge bar 16 which is supported by the legs 17 that extend upwardly from the cylindrical portion 15. This bridge bar has the central hole 18 adapted to receive the rubber thread 19 passing upwardly through the hollow spindle 11. Each leg 17 is preferably provided with a thread receiving hole 20 through which the covering yarn Y supplied by the package 12 can be threaded. This yarn Y is shown in full lines in one position and in dot and dash lines in two positions of Fig. 1. The purpose of providing a hole 20 in each leg 17 is to make the cap easier to thread up, and also make the cap balanced as to centrifugal forces. The two holes will serve also to reduce the wear of the yarn upon the walls of each guide hole 20, since sometimes the yarn will be threaded through one hole 20 and other times through the other hole 20.

The cap just described may be formed of metal, but is preferably formed of some such tough durable plastic material as nylon which is light in weight, non-corroding, easy to keep clean and offers good resistance to the wearing action of the rubber thread and covering yarn. The cylindrical portion 15 of this cap is preferably so made that it will frictionally engage the outer face of the outer race 21 of the anti-friction device to be

described, and this sleeve is preferably provided with a slight shoulder at the lower end of each leg 17 which forms a stop adapted to engage the upper edge of the race ring 21 as shown in Fig. 2. 5 This prevents the cap from being pushed down too far upon the race ring.

The anti-friction bearing employed to rotatably support the cap 14 upon the upper end of the hollow spindle 11 can be variously constructed and as shown comprises the outer race ring 21, inner race ring 22 and anti-friction balls 23. The inner race ring 22 is fitted tightly upon the relatively long, hollow, bearing post 24 which post fits snugly in the adapter bushing 25 that fits within the bore of the hollow spindle 11. This bushing is locked in place by providing it with the annular recess 26 that receives the set screw 27 threaded in the upper portion of the hollow spindle 11. The arrangement is such that the cap supporting means just described may be assembled on the hollow post 24, and then this post is forced tightly into the bushing 25. This bushing is then inserted in the upper end of the spindle 11 and locked in this position by the set screws 27.

20 The rubber threads supplied to the covering apparatus usually has a thin coating of talc on its outer surface to give it a smooth surface that will run freely. Some of this talc is likely to become dislodged from the thread at the lower end of the hollow post 24. This talc is prevented from reaching the anti-friction bearing from a point below the same by the construction shown, whereby tight joints are formed that keep the talc from working upwardly around the outer surface of the post 24, and such talc as passes upwardly through the central passage of this post is prevented from falling into the bearing by the outwardly flaring upper end 28 of this post. The talc which becomes dislodged from the rubber thread 19 at the lower end of the post 24 is disposed of by providing the hollow spindle 11 with the four laterally disposed holes 29 which form talc outlet passages, through which air will pass outwardly under the centrifugal force produced by the rapidly rotating spindle to carry the talc out to these holes.

25 The cap 14 constructed as above described provides a number of advantages; one being that the yarn tensioning and guide means comprises parts located within the diameter of the cap and has no structure extending laterally beyond the cylindrical portion 15 of the cap; and another advantage resides in the ease with which the cap can be attached to and removed from its supporting bearing when it is desired to clean or replace the cap. An extremely important feature of the present cap resides in the bridge bar above described which acts upon the covering yarn Y to supply it to the covering point under the desired tension. If it is desired to supply the yarn Y to the covering point under minimum tension, then this yarn should be threaded through a hole 20 and direct to the covering position as shown in Fig. 3. If a somewhat greater tension is desired this yarn Y may be led through a hole 20 and then laterally and upwardly against a side of the bridge bar to slide thereagainst as it passes to the covering point above this bridge bar, as shown in Fig. 2. If a still higher degree of tension upon the yarn Y is desired, this yarn may be led through a hole 20 and then looped more than half way around the bridge bar as shown in Fig. 4, to pass to a covering position below this bridge bar. The bridge bar 21 in addition to controlling the tension at which the yarn Y is supplied to the cover-

ing point, serves also to control the location of this covering point and prevent it from hunting up and down.

Having described how the cap of the present invention may be employed upon a core covering device to guide and tension the covering yarn, it will now be described as employed to twist a single yarn, or ply twist two or more yarns together. In this connection it is desired to point out that the construction of the cap may be the same for all of these used and it is shown the same in all views of the drawings.

The apparatus of Figs. 7 and 8 shows a single yarn as being twisted. In Fig. 7 there is shown the solid spindle 30 on which there is frictionally mounted the adapter sleeve 31 having secured to its upper end the thick adapter head 32. On this adapter is mounted the paper tube 33 of usual construction and having wound thereon the supply of yarn 34, from which the yarn strand 35 extends upwardly.

Since the spindle 30 is not used as a core covering device it is shown solid in Fig. 8, and at the top of this spindle is mounted the cap 14, above described, and comprising the cylindrical body 15 and bridge bar 16. This cap has the holes 20 in the legs 17 of the bridge bar and has the central hole 18 and the cap fits snugly on the outer race ring 21 as above described. The antifriction bearing comprising the balls 23 mounted between the rings 21 and 22 is preferably supported upon the spindle 30 by the parts 24, 25, 26 and 27 above described.

In employing the apparatus shown in Figs. 7 to 10 inclusive, it is assumed that the single yarn or ply yarn is being pulled upwardly at a uniform speed by power driven rolls not shown. The single yarn 35 of Figs. 7 and 8 is shown as being twisted under a minimum amount of tension, and to this end the yarn passing through a side guide hole 20 and then directly to the central hole 18 to impart to this yarn the desired number of turns per inch. It then passes upwardly as indicated by the arrow. This cap will place very little tension on the yarn and permit a low twist yarn to be twisted at high speed without breaking.

The cap 15, 16 is shown in Fig. 9 as being employed to ply two yarns together to produce the ply yarn 36 and the desired amount of tension is exerted upon this yarn by bringing it inwardly along one side of a leg 17 to pass through the hole 20 and then it passes around this leg to the central hole 18. The two yarns forming the ply 36 are wound side by side on the package 34.

The cap 15, 16 is shown in Fig. 10 as subjecting the single yarn 37 being twisted to high tension in that this yarn is shown as passing through one guide hole 20 and then across the cap to the other guide hole 20 before it passes to the central hole 18. It will be apparent however that the yarn or yarns from the supply package may be twisted in various ways around the legs 17 to secure the desired tension.

While the cap 14 is herein shown and described as mounted on the hollow spindle 11 or on the solid spindle 30, it may also be supported from the above mentioned adapter head 13', against which the yarn rests when it is not thrown outwardly by the rapid rotation of the spindle. In any case the cap should be small enough to permit the yarn package to be doffed without disturbing the cap.

It will be seen from the foregoing that the cap construction of the present invention possesses

a number of advantages, and that it is simple and symmetrical in construction, and provides means whereby the tension exerted upon a covering yarn or yarn being twisted can be made as slight or as great as desired, also that the antifriction bearing that supports the cap is well protected from the talc powder that may become dislodged from the rubber core being covered. The cap 14 being light in weight and compact in construction lends itself to the high speed production of the elastic yarn E and to the yarn twisting operations above described.

Having thus described my invention, what I claim and desire to protect by Letters Patent is:

1. A core covering device capable of operating at high speed, comprising in combination a hollow spindle having means for rotating it at high speed and adapted to support a package of core covering yarn, a cap rotatably supported by an antifriction bearing at the top of said spindle to turn freely independently of the spindle, a bridge bar secured to said cap and provided with a central core hole and with a laterally disposed yarn hole, and said bridge bar being constructed and arranged so that the covering yarn can be threaded up so that it will drag against a side of the bridge bar to tension it as it passes from said yarn hole to the core covering position.

2. A core covering device capable of operating at high speed, comprising in combination a hollow spindle having means for rotating it at high speed and adapted to support a package of core covering yarn, a plastic cap rotatably supported by an antifriction bearing at the top of said spindle to turn freely independently of the spindle and formed with a bridge bar, said bridge bar being provided with a central core hole and with a laterally disposed yarn hole and positioned so that the covering yarn can be threaded up in a manner to drag against a side of the bridge bar to tension it as it passes from said yarn hole to the core covering position.

3. A core covering device capable of operating at high speed, comprising in combination a hollow spindle having means for rotating it at high speed and adapted to support a package of core covering yarn, a cap rotatably supported by antifriction means at the top of said spindle to turn independently of the spindle, a guide bar extending upwardly and inwardly from adjacent an outer edge portion of the cap and provided with a core guide and a yarn guide and constructed so that the covering yarn can be threaded up to drag around part of this bar to tension it as it passes from said yarn guide to the core covering position.

4. A core covering device, comprising in combination a hollow spindle having means for rotating it and adapted to support a package of core covering yarn, a cap rotatably supported by an antifriction bearing at the top of said spindle to turn freely independently of the spindle and having a yarn guiding eye for guiding a covering yarn towards the core to be covered, said antifriction bearing having an inner race ring tightly secured to said spindle with a talc tight joint, and an outer race ring that engages and supports the cap.

5. A core covering device, comprising in combination a hollow spindle having means for rotating it and adapted to support a package of core covering yarn, a cap rotatably supported by an antifriction bearing at the top of said spindle to turn freely independently of the spindle and having a bridge bar secured to the cap and pro-

vided with a core receiving guide eye and a yarn guide eye for guiding the yarn to the core covering position.

6. In a device of the class described, a yarn supporting spindle having means for rotating it and a yarn package thereupon, a cap rotatably supported by an antifriction bearing at the upper end of said spindle to turn freely independently of the spindle, a bridge bar secured to said cap and provided with a central hole and with a side hole, and said bridge bar being constructed and arranged so that yarn from said package can be threaded up so that it will drag against a side of the bridge bar to tension such yarn as it passes from said side hole toward the 15 central hole.

7. In a device of the class described, a yarn supporting spindle having means for rotating it and a yarn package thereupon, a cap rotatably supported by an antifriction bearing at the upper end of said spindle to turn freely independently of the spindle, said cap comprising a cylindrical body having oppositely spaced legs extending upwardly therefrom and connected by a horizontal bar, the horizontal bar being provided with a central hole and each leg with a yarn hole, so that yarn from said package can be tensioned by causing it to drag around a leg as it passes from a yarn hole toward said central hole.

EDWIN G. EGGE.
